UNITED STATES PATENT OFFICE.

HENRI DOLTER, OF LIMOGES, FRANCE.

APPARATUS FOR THE MANUFACTURE OF EARTH METALS.

Application filed October 27, 1924. Serial No. 746,149.

To all whom it may concern:

Be it known that I, HENRI DOLTER, citizen of the French Republic, residing at Limoges, Haute-Vienne, in the French Republic, have invented new and useful Improvements in Apparatus for the Manufacture of Earth Metals, of which the following is a specification.

The present invention has for its object an apparatus for the manufacture of earth metals and particularly adapted for carrying out the improved method of electrolytic manufacture of said metals which consists in melting the electrolyte within the electrolytic tank and maintaining the said electrolyte in the liquid state, by means of gas radiators, and preferably flameless combustion gas radiators, immersed within the electrolyte.

One advantage of the use of my new apparatus resides in that the electric current is now used solely to decompose the already melted electrolyte, whereby I obtain a great economy in electric power, which considerably reduces the cost of the metal.

A further feature of my improved apparatus consists in that the electrolytic tank forming part of the apparatus, has a low electric resistance, which is possible since no Joule effect for heating the electrolyte and melting the same is now necessary, and which permits of connecting in series a greater number of tanks than is admissible with the known apparatus, and hence of employing electric generators of usual construction and working normally at usual voltage.

The appended drawings show by way of example an embodiment of the apparatus according to the invention and particularly adapted for the manufacture of aluminium.

Fig. 1 is a plan view of the apparatus, the plates covering the tank being removed.

Fig. 2 is a cross section on the line 2—2, Fig. 1.

Fig. 3 is a longitudinal section of the tank on the line 3—3, Fig. 1.

Fig. 4 is a diagrammatic plan view of a plant consisting of a plurality of apparatus according to the said invention.

The apparatus, or electrolytic tank, comprises a metallic tank 1 which is strengthened by outer iron fittings 2 and is lined with a good electric conducting substance 3 which preferably consists of bricks of compressed coal or petroleum coke and the faces

whereof are planished after baking. Said bricks are jointed by means of a liquid mortar of the same material made up with glucose and ground into an impalpable powder. In certain cases it may prove advantageous to cover the parts of the said lining which are not to enter into contact with the electrolyte with a metallic coating, for instance of the same metal than that produced in the tank, or of copper, said layer being formed of an electrolytic deposit or obtained by spraying pulverized metal by means of any known apparatus such as a Schopp pistol. But in the particular case of the production of aluminium, this layer is not required.

The resulting tank will form an excellent conducting mass and it is connected to the negative pole of the source of current. The tank and its lining are electrically insulated from earth by insulating supports 4 made of any suitable substance.

The apparatus comprises also gas radiators designed for heating the electrolyte and melting the same within the tank; said radiators comprise one, two or a greater number of metallic tubes 5, for example of steel or nickel, extending longitudinally through the tank and disposed in recesses 6 formed in the conducting lining of the tank. Said tubes are electrically connected to the tank 1, i. e., to the cathode, in order to obviate any difference of potential between the radiators and the inner lining of the tank, whereby all chemical action upon the tubes will be avoided. For this purpose, the said tubes are immersed in a mass of melted aluminium 7 filling each of the recesses 6, said mass being for example obtained during the first operation performed in the tank and consisting of the portion of melted metal which is situated below the inlet 8 of the channel 9 for pouring the metal, said channel being normally closed by a carbon plug 35.

The above described means for connecting the radiator tubes to the electrolytic tank is found to be particularly advantageous in the manufacture of aluminium. But it is obvious that the tubes may be connected to the cathode in any other suitable manner; for example the various radiator tubes may be secured or suspended to a removable metallic cross-piece carried by the tank, the same being directly electrically connected to the negative pole of the source of current or to the walls of the tank. In this event, in

order to avoid all oxidation and consequent destruction of the said tubes, these latter must be covered with a layer of the same metal which is produced in the tank, aluminium in the present case, said layer being formed of an electrolytic deposit or obtained by spraying pulverized metal by any known suitable means.

10 The tubes 5 are filled with a granular and porous refractory substance as is usually employed in flameless combustion gas radiators.

15 The inlet end of each tube 5 is connected to a combustible gas supply pipe and to a compressed air pipe, but is electrically insulated therefrom, said connection being effected in the following manner.

20 The inlet of each tube 5 is connected by a flange 10 to a socket 11 into which open a branch pipe 12, of the gas supply main pipe and a branch pipe 13 of the air main pipe. Said branch pipe 12 is connected to the socket 11 by an electrically insulating section of pipe 14 (e. g., of porcelain). The 25 compressed air branch pipe 13 is connected to the socket 11 by an insulating section 15 and a pipe 16 which is surrounded for a part of its length by a casing 17 which communicates, through the medium of a three-way 30 priming cock 18, with the burnt gas outlet end of a second tube 5 adjacent the inlet end under consideration and situated at the same side of the apparatus. The casing or jacket 17 thus constitutes a heat exchanger 35 providing for the heating of the compressed air before the latter is mixed with the combustible gas in each of the sockets 11. The casing 17 is also connected to the main exhaust pipe of the plant by an insulating section 19 and a branch element 36. In this manner, the set of radiator tubes 5, connected to the cathode, is well insulated from the outer piping of the plant. It will be seen in the drawing that, due to this arrangement, the apparatus comprises at each end like connections of the tubes 5 with the gas and the compressed air supply pipes and with the exhaust pipes and that the gases are circulated in opposite directions in any 45 two adjacent tubes, according to the arrows 50 28 and 29.

55 Although the radiators shown in the drawing consist of straight metallic tubes, it is obvious that the tubes may be given any other suitable shape, and may be made of any other suitable substance having a good heat-conduction, for example graphite, alumina or silica.

60 The anode which is immersed in the tank comprises one or more carbon blocks 20, each having imbedded therein a metal suspension rod 21. The upper part of each rod forms a rack 22, or is provided with a screw, said rack or screw being operated in 65 any known manner, either by hand or by

means of a small electric motor, so that it may be raised or lowered—automatically or not—according to the electric resistance of the said tank. The said electrode is connected to the positive pole of the source of 70 current.

The tank may be covered by suitable plates 23 which are for example of carbon, leaving however a sufficient passage way for the anode. The said plates are provided 75 with apertures 24 which are closed during the initial melting period by plugs provided with handles, and through which suitable quantities of salts and oxides are supplied from time to time; said apertures also 80 provide for the escape of the gases produced in the tank.

85 Each operation carried out in the above described apparatus is performed as follows:

90 The salts or oxides constituting the electrolyte, i. e., a mixture of alumina and cryolite are first introduced into the tank; the gas supply valves 25 of the radiators are opened, and the three-way cocks 18 are 95 turned so as to connect the interior of the tubes 5 directly to the atmosphere through the medium of the nozzles 26 of the cocks 18. The gas issuing from said nozzles 26 is thus ignited and the air supply cocks 27 95 are gradually opened. The flames will gradually diminish and will become extinguished, and at this time the porous refractory substance in the tubes 5, which has become incandescent, will raise the temperature in 100 the said tubes to 950° C., and the salts and oxides composing the electrolyte, together with the mass of aluminium surrounding the said tubes, will be melted.

105 When the said salts and oxides of the electrolyte are melted, fresh quantities of alumina are supplied according as the alumina becomes dissolved, and when the bath has attained the normal composition, the electric current is sent into the tank; further 110 quantities of alumina are supplied according as the aluminium is deposited.

115 As above indicated, the position of the anode, according to the resistance of the whole apparatus (i. e., tank and bath), can be regulated automatically in the known manner by means of an electric motor controlled by a relay.

120 At stated intervals, the metal in the tank, is cast by removing the carbon plug 35 normally closing the channel 9.

Inasmuch as the tank and its lining are so constructed as to have but a low electric resistance, and on the other hand the E. M. F. required for the decomposition of the 125 alumina varies from 28 to 3 volts, a complete plant for the manufacture of aluminium may be constituted by connecting in series for instance forty apparatus such as herein described, thus allowing the use of 130

known types of electric generators working normally at the usual voltage of 110 to 120 volts.

A plant of this nature is shown diagrammatically in Fig. 4, and said figure shows that for each of the successive apparatus 30, the anode is connected to the tank of the succeeding apparatus, the anode of the first apparatus being alone connected to the positive terminal of the source of current, whilst the tank of the last apparatus is connected to the corresponding negative terminal. For each apparatus, the respective pipes 12, 13 and 36 for the gas and the compressed air supply and the exhaust of the combustion gases, are connected to the respective main pipes of the plant 32, 33 and 34 for the gas and the compressed air supply and for the discharge.

Obviously, the said invention is not limited to the use of the above-mentioned details of construction of the apparatus, these being susceptible of all desired modifications without departing from the spirit of the invention.

Having now described my invention, I declare that what I claim as new and desire to secure by Letters Patent is:

1. In an electrolytic tank for the manufacture of earth metals, the combination of tubes extending through the tank, means for supplying a combustible gas to said tubes, means for supplying compressed air to said tubes and a granular and porous refractory substance within said tubes, whereby a flameless combustion is obtained.

2. In an electrolytic tank for the manufacture of earth metals, the combination of tubes extending through the tank, means for electrically connecting said tubes to the cathode of said tank, means for supplying a combustible gas to said tubes, means for supplying compressed air to said tubes, and a granular and porous refractory substance within said tubes, whereby a flameless combustion is obtained.

3. In an electrolytic tank for the manufacture of earth metals, the combination of tubes extending through the tank, means for electrically connecting said tubes to the cathode of said tank, a layer of the same metal as that produced in the tank covering said tubes, means for supplying a combustible gas to said tubes, means for supplying compressed air to said tubes and a granular and porous refractory substance within said tubes, whereby a flameless combustion is obtained.

4. In an electrolytic tank for the manufacture of earth metals, the combination of tubes extending through the tank, means for electrically connecting said tubes to the cathode of said tank, a layer of the same metal as that produced in the tank covering said tubes, pipes for supplying a com-

bustible gas to said tubes, pipes for supplying compressed air to said tubes, exhaust pipes for discharging the burnt gases from said tubes, electrically insulating members for connecting said pipes to said tubes and a granular and porous refractory substance within said tubes, whereby a flameless combustion is obtained.

5. In an electrolytic tank for the manufacture of earth metals, the combination of tubes extending through the tank, means for electrically connecting said tubes to the cathode of said tank, a layer of the same metal as that produced in the tank covering said tubes, pipes for supplying a combustible gas to said tubes, pipes for supplying compressed air to said tubes, exhaust pipes for discharging the burnt gases from said tubes, the exhaust pipe of one tube surrounding a portion of the air supply pipe for an adjacent tube, electrically insulating members for connecting said pipes to said tubes and a granular and porous refractory substance within said tubes, whereby a flameless combustion is obtained.

6. An electrolytic tank for the manufacture of earth metals comprising in combination a metal tank, an inner lining of carbon bricks for said tank, said bricks having all their faces planished, the tank together with said lining constituting the cathode of the apparatus, tubes extending through the tank below the normal level of the electrolyte in said tank, means for electrically connecting said tubes to said tank, means for supplying a combustible gas to said tubes, means for supplying compressed air to said tubes and a granular and porous refractory substance within said tubes, whereby a flameless combustion is obtained.

7. An electrolytic tank for the manufacture of earth metals comprising in combination: a metal tank, an inner lining of carbon bricks for said tank, said bricks having all their faces planished, the tank together with said lining constituting the cathode of the apparatus, a layer of the same metal as that produced in the tank coating the portions of the tank walls above the normal level of the electrolyte in said tank, tubes extending through the tank below the normal level of the electrolyte in said tank, means for electrically connecting said tubes to said tank, means for supplying a combustible gas to said tubes, means for supplying compressed air to said tubes and a granular and porous refractory substance within said tubes, whereby a flameless combustion is obtained.

8. An electrolytic tank for the manufacture of an aluminium comprising in combination: a metal tank, an inner lining of carbon bricks for said tanks, said bricks having all their faces planished, the tank

together with said lining constituting the cathode of the apparatus, channels formed in the bottom wall of said inner lining, cast aluminium filling said channels, tubes extending through said channels and imbedded within said cast aluminium, means for supplying a combustible gas to said tubes, means for supplying compressed air to said tubes and a granular and porous refractory substance within said tubes, 10 whereby a flameless combustion is obtained.

In testimony whereof I have signed my name to this specification.

HENRI DOLTER.
